UNITED STATES PATENT OFFICE.

HESS P. MORGAN, OF LISBON, OHIO.

MINING MACHINE.

Application filed March 31, 1924. Serial No. 703,137.

To all whom it may concern:

Be it known that I, HESS P. MORGAN, a citizen of the United States, and a resident of Lisbon, in the county of Columbiana 5 and State of Ohio, have invented a new and useful Improvement in Mining Machines, of which the following is a specification.

This invention relates to mining machines, and particularly to the type adapted to cut 10 kerfs during the mining of coal or similar materials.

It is an object of the invention to provide a device which is simple, compact, strong and durable, which is self-contained so as 15 to be conveniently transported from place to place, which can be manufactured at a reasonable cost, which will not easily get out of order, and which will function efficiently for the purpose intended.

20 It is a special object to provide a machine of the character referred to which can be selectively driven by motor or actuated manually, as desired, and in which the man-power can be conveniently varied according 25 to working conditions without changes in the mechanism employed.

It is also a special object to provide effective means both for rotating the cutting elements used as well as advancing such 30 elements bodily into the wall formed by the material operated upon, and so associated that the mechanism may be set with ease to obtain either result desired.

Other special objects are to provide a 35 mining machine equipped with a pair of closely spaced cutting disks which are mounted upon a single integral hub of novel construction in a unique fashion, in which the cutting disks are of novel form, in 40 which the peripheral teeth for the disks are not only removable but reversible so as to enable the same cutting effect to be obtained regardless of the direction of rotation of the disks, and in which the relative dimensions, 45 disposition and formation of the several teeth are such that the cutting portion of the machine is rendered practically self-cleaning in that the entire material between the lines of cut produced by the two spaced 50 disks is readily removed under the action of the said teeth.

These and other objects of the invention will more fully appear when taken in conjunction with the following description and 55 the appended claims.

In the accompanying drawings, Fig. 1 is a side elevational view illustrating one embodiment of the invention; Fig. 2 a vertical sectional view, with parts in elevation, of the machine shown in Fig. 1; Fig. 3 a plan view of the machine; Fig. 4 a fragmentary view, partly in elevation and partly in section, showing in detail the construction of one of the cutting disks; Fig. 5 a detail elevation of one of the larger teeth used on the 60 cutting disk; Fig. 6 a similar view showing one of the smaller cutting teeth; Fig. 7 a transverse sectional view taken on the line VII—VII of Fig. 3; Fig. 8 a similar view taken on the line VIII—VIII of Fig. 3; Fig. 70 9 an end elevation looking in the direction of the arrows IX—IX of Fig. 3; Fig. 10 a fragmentary view, in plan, showing in detail the construction of the beam carrying the cutting disks, together with the adjusting means 75 therefor; Fig. 11 a vertical sectional view of the parts illustrated in Fig. 10, the section being taken substantially on the line XI—XI of said figure; Fig. 12 a detail sectional view showing the structure of the 80 integral hub forming a part of the cutting head; Fig. 13 a transverse sectional view taken substantially on the line XIII—XIII of Fig. 10; Fig. 14 a plan view illustrating the machine forming the subject of this 85 invention arranged within a "room" for cutting a horizontal kerf thereacross; and Fig. 15 an elevation of the parts shown in Fig. 14.

The frame of the machine comprises the side members 1, 1', the end members 2, 2' 90 and the floor or bottom 3, and preferably the frame is made rectangular in shape. Surmounting the end member 2, and suitably fixed thereto, is a bearing bracket 4 provided with the bearing bosses 5 and 6. 95 A similar bearing bracket 4' is fixed to the end member 2', and is provided with corresponding bearing bosses 5' and 6'.

A driving shaft 7 is journaled at its opposite ends in the bosses 5 and 5', and has 100 rigidly attached thereto throughout its length the gears 8, 9 and 10. The driving shaft also carries a bevel pinion 11, this pinion being formed at the end of a sleeve 12 rotatably journaled in a bearing sleeve 13. The pinion 11 and its sleeve 12 is longitudinally slidable upon the driving shaft, but rotatable therewith, such connection being effected by splining the same 105 up on the shaft, a key or feather 14 engaging 110

- a groove 15 formed in the driving shaft and extending substantially its full extent between the gears 8 and 9.
- 5 A short shaft 16 is rotatably mounted in the bearing boss 6 located at the upper end of the bracket 4, is equipped with the actuating handles 17 and 18 at its opposite ends, and has also fixed thereto the gear 19 which meshes with the gear 8 on the driving shaft
- 10 7. A similar shaft 16' is mounted in the boss 6', is equipped with the actuating handles 17' and 18' at its opposite ends and carries a gear 19' which meshes with the gear 10 on the driving shaft.
- 15 15. The lower edge of the end member 2' of the frame is provided with an elongated opening 20 through which slidably extends a beam 21, the relative sizes of the opening and the beam assuring a guiding effect for
- 20 20 the beam during its reciprocating or longitudinal sliding movement within the frame, the bottom face of the beam preferably lying in contact with the upper face of the floor 3, as clearly shown in Fig. 2 of the
- 25 drawings. The beam 21 comprises two sections, the terminal of the front section being indicated at 21' while the rear section of the beam is indicated at 21''. The rear section 21'' is angular in shape, the two
- 30 30 limbs thereof forming preferably a right angle, one limb being connected to the terminal portion 21' of the front section of the beam by a tongue and groove connection (see Fig. 13), while the upstanding limb of the
- 35 rear section 21'' carries rigidly attached thereto the bearing sleeve 13. The front and rear sections of the beam may be adjusted longitudinally of each other by means of a rotatable shaft 22 having one
- 40 40 end rotatably mounted in a pair of spaced ears 23 with the polygonal portions 22' between the said ears enlarged in cross-section, and having its other end externally threaded and engaging an interiorly threaded opening 24 formed in the body of the horizontal limb of the rear section of the beam.
- 45 45. Although the coaction between the beam and the opening 20, as well as the slidable suspension of the pinion 11, which is carried by the rear section of the beam, effectively support the beam for sliding movement longitudinally of the frame, in order to positively preclude a tendency of the beam to rotate about the driving shaft as an axis, a
- 50 50 cross-bar 25 is fixed to the rear section 21'', and has its opposite extremities fitting within grooves formed on the side members of the frame by means of spaced guiding ribs such as indicated at 26 and 26', as shown
- 55 55 in Fig. 8.
- Bolted to the rear section of the beam, and upstanding therefrom is a bearing pedestal 27 in which is suitably journaled an auxiliary shaft 28 having attached at its opposite
- 60 60 ends a bevel pinion 29 and a sprocket wheel
30. The pinion 29 meshes with the pinion 11, while the sprocket wheel, carried at the lower end of the auxiliary shaft, cooperates with an endless sprocket chain 31 which is twined about the intermediate geared portion of an integral hub 32 mounted for rotative movement in and carried by the free end of the beam 21. This chain is preferably equipped with a plurality of cleaning lugs 31.
- 75 75. Also anchored for rotative movement, but held against longitudinal movement, within the frame is a screw shaft 33, which engages an internally threaded boss 34 carried at one side of the bearing pedestal 27.
- 80 Telescopically engaging the end of the screw shaft anchored in the frame is a sleeve 35 suitably journaled in the end member 2 which has integrally formed therewith the gear 36 adapted to mesh with the gear 8 on the driving shaft, the sleeve 35 and gear 36 being splined to the screw shaft so as to be bodily slidably thereon. One end of the sleeve 35 is provided with a pair of spaced annular grooves 37, 38, which are adapted to
- 90 be engaged by a spring pressed pin 39 fixed to the front face of the end member 2. When the pin 39 engages the groove 37 the sleeve 35 is so positioned as to bring the gear 36 into meshing relation with gear 8 while
- 95 the relative disposition of these parts when the pin 39 engages the groove 38 is such that the gear 36 is held in the position shown by the dotted lines 40, in Fig. 2 of the drawings, and out of mesh with the gear 8.
- 100 An electric or other suitable driving motor may, if desired, be provided at one end of the frame, such a motor being indicated at 41 and its armature shaft at 42. Suitably journaled in the end member 2', and telescopically engaging the armature shaft 42 for sliding movement thereupon is a sleeve 43 having formed integrally therewith a gear 44, the sleeve and gear 43-44 corresponding in construction to the sleeve and gear 35 and 36, previously described. The gear 44 is adapted to be operatively connected or disconnected, at will, with the gear 10, and locked in these positions by means of a spring pressed pin 45, corresponding to
- 110 the pin 39, all as clearly indicated at the right hand side of Fig. 2 of the drawings.
- 115 As previously noted, the free end of the beam 21 carries a rotatably mounted hub 32 thereon. This hub comprises but a single integral piece having an enlarged central portion 32^a, at each side of which is a reduced bearing portion 32^b, and beyond each of the bearing portions is a reduced shouldered terminal as indicated at 32^c. The enlarged central portion 32^a around its periphery is equipped with a series of sprocket teeth forming a sprocket gear for cooperation with the sprocket chain 31. A main axial bore 46 extends through the body of

the hub, which is also provided with the bores 47, 47', 48, 49 and 49'. The hub is rotatably mounted in circular openings in a pair of spaced plates 50, 50', suitably anchored to the free end of the beam 21 as by bolts or rivets indicated at 51, the bearing portions 32^b of the hub cooperating with the openings in these plates, and, if desired, annular bushings such as shown at 52 and 52' may be employed. Fixed to the reduced terminal portions 32^c of the hub is a pair of spaced cutting discs 53, 53', the inner surfaces of which lie in close proximity to the outer faces of the plates 50, 50'. Each of the cutting discs is provided with a central aperture fitting over the reduced terminal portion of the hub and having spaced notches formed therein as indicated at 54, 54', for receiving the pins 55, 55', fitting within the bores 47 and 47', respectively, and terminating flush with the ends of the hub. A bolt 56 extends completely through the main axial bore 46 and serves to bind a pair of washers 57, 57' into binding relation with the ends of the hub for the purpose of holding the parts in assembled relation and for binding the cutting discs 53, 53' into intimate contact with their seats upon the terminal shoulder portions of the hub. The bores 49, 49' extend radially of the hub and serve as auxiliary conducting channels extending from the bore 48 to the bearing surfaces 32^b, providing means for conducting lubricant stored within the bore 48 to the said bearings.

Each of the cutting discs 53, 53' is similarly constructed with the exception of the direction in which the several teeth mounted therein are projected, and only one of these discs need therefore be described in detail. The disc 53 (see Fig. 4) is provided around its periphery with a series of spaced symmetrically formed notches or recesses 58, the bottom portion of the notches being substantially semi-circular in shape but provided at the portions adjacent the periphery of the disc with what may be termed abutments 59. Lockingly fitting within these notches or openings 58 are a series of cutting teeth 60 and 61, the teeth 60 being considerably smaller in size than the teeth 61, as shown in Fig. 4. The base portions 62 of both the larger and smaller teeth are somewhat thicker than the disc 53, and each is provided with a groove 63 corresponding in outline or contour to the opening 58, the terminals of the groove forming shoulders which are adapted to abut against the periphery of the disc as shown at 64, and the portions of the disc surrounding the opening 58 snugly fitting within the groove whereby the abutment portions 59 and the shoulder 64 serve to lockingly anchor the teeth against rocking or pivotal movement with respect to the disc, while at the same

time permitting the teeth to be bodily withdrawn radially of the disc, and for the purpose of permitting the easy withdrawal of the teeth in a radial direction an aperture 65 extends through the thickened base of each tooth through which any suitable instrument may be projected for this purpose.

The detailed construction of both the larger and smaller teeth is clearly shown in Figs. 5 and 6 of the drawings, and since the construction thereof as far as described is identical, the several features have been indicated throughout by the same reference numerals. As shown in Figs. 1 and 2, however, the larger teeth 61 on both discs 53 and 53' are bent or projected laterally away from the space between the discs, while the smaller teeth 60 on both discs are projected laterally towards the space between the discs, and lie in close proximity to the upper and lower faces of the beam 21 beyond the plates 50 and 50'.

The entire construction of the cutting head is exceedingly compact, yet sturdy and strong, and so associated as to enable the cutting discs to be spaced but a short distance apart so as to bring the smaller cutting teeth 60 into such close proximity as to effectively remove the entire material lying between the lines of cut produced by the larger teeth 61.

Suitably journaled for rotative movement in a pair of spaced bearings 70, 70' carried upon the side member 1' of the frame is a winding shaft 71 having the winding drum 72 fixed thereon, and for the purpose of selectively connecting and disconnecting the shaft 71 from the gear 9 fixed to the driving shaft 7 is a slidable pinion 73 formed integrally with a sleeve 74 telescopically engaging the winding shaft and the bearing 70', and corresponding to the construction of the sleeves and gears 35, 36 and 43, 44. Fixed at the opposite ends of the frame are eyelets 75, 75' and 76, 76', and rigidly attached and projecting from the opposite ends of the frame are the pairs of supporting brackets 77, 77' and 78, 78'.

In operation, the frame of the machine is positioned at a desirable point in front of the vein or stratum of material to be operated upon, and with the beam 21 in the retracted position illustrated in Figs. 1 to 3 of the drawings. The beam 21 with its cutting head may be advanced by rotating the screw shaft 33, such rotation being accomplished by bringing the gear 36 into mesh with the gear 8. With the parts thus adjusted, power may be transmitted manually to the shafts 16, 16' and through the gearing interposed between said shafts and the driving shaft 7 to cause rotation of the pinion 11. As long as the gear 36 is in mesh with the gear 8, rotation of the shaft 7 will cause rotation of the screw shaft 33 which,

due to its cooperation with the internally threaded boss 34 on the pedestal 27, will cause beam 21 to be moved forwardly within the frame so as to bodily advance the entire cutting head mounted at its free end into cutting relation with the material to be operated upon. At the same time, rotation of the gear 11 will through the pinion 29, auxiliary shaft 28, sprocket wheel 30, 10 sprocket chain 31, and sprocket gear 32 cause bodily rotation of the hub 32 and the cutters mounted thereon.

The series of larger teeth 61 on the spaced disks 53 and 53', produce two separated 15 lines of cut, while the series of smaller teeth, the smaller teeth being preferably interposed between the larger teeth, not only assist in the cutting action upon the material but due to their lateral projection within 20 the space between the cutting disks and their close proximity to each other effectively remove the entire material between the lines of cut produced by the larger teeth. The broken material accumulating between the 25 disks adjacent the hub 32 is removed by means of the lugs 31' fixed to the chain 31, in an obvious fashion.

Due to the provision of the pair of shafts 16, 16', the driving shaft 7 may be rotated 30 manually by workmen placed at either or both ends of the frame, and the man power applied may be varied as desired within the limits provided by the number of handles 17, 18'.

In the event that it is desired to operate 35 the shaft 7 by means of the motor 41, either independently or simultaneously with the application of power by the workmen actuating the shafts 16, 16', it is merely necessary to move the gear 44 into mesh with the 40 gear 10. The motor 41 is intended for use under unusual conditions, power being primarily applied to the drawing shaft by means of the actuating handles described.

During the actuation of the screw shaft 33, the forward bodily movement of the beam 21 is accompanied by like movement of the pedestal 27 and the operative connections between the pinions 11 and 29, the 50 pinion 11 and its sleeve 12 sliding forwardly on the driving shaft due to its splined connection therewith.

In Figs. 14 and 15, the machine is illustrated as mounted for operation within a 55 "room" 80, and in order to suitably suspend the machine in working position for cutting kerfs transversely of the room, a plurality of vertical standards 81, 82, 83 and 84 is provided, commonly disposed in the 60 positions illustrated in said figures. Each of the standards is provided at its upper end with a screw bolt 83 which is threaded within the body of the standard so that upon turning movement thereof the same will be 65 projected forcibly against the ceiling of the

"room" to securely hold the standard in position, the nut 86 being provided to hold the parts in locked position. A horizontal beam 87 is attached to the standards 81 and 82 in any suitable manner as by the notched blocks 88, 88' of well known construction, while a similar beam 89 bridges the space between and is likewise attached to the upright standards 83 and 84. The beams 87 and 89 may be located at any desirable height, the 70 position which they assume when a line of cut is desired to be made adjacent the floor being designated by the showing in Fig. 15, it being understood, however, that the height of the blocks 88, 88' may be adjusted to any 75 desired position for producing the line of cut at the desired height above the floor of the room. The frame is bodily supported upon the beams 87 and 89 by means of the supporting brackets 77, 77', and 78, 78' located at the opposite ends of the frame, these bearing brackets engaging the upper edges of the beams 87 and 89 in the manner clearly shown in Fig. 14.

The frame, as illustrated in Figs. 14 and 15, is supported for cutting a kerf adjacent the floor of the room, and for supporting the parts for this purpose, the lower faces of the brackets 77-78' engage the upper edges of the beams 87 and 89. Whenever it is desired to cut a kerf adjacent the ceiling of the room, it is obvious that the entire machine may be upturned, with the upper faces of the supporting brackets 77 to 78' lying in contact with the upper edges of the beams 87 and 89, in which position the bottom or floor 3 of the frame will lie adjacent the ceiling of the room.

When a kerf is to be formed across the entire width of the room, it is customary to first force the cutting head to the required depth into the material at one side of the room and then bodily move the cutting machine transversely of the room by sliding the entire machine along the beams 87 and 89, thus producing a line of cut thereacross. For the purpose of sliding the frame bodily upon the supporting beams, a cable 90 is passed through a pulley or sheave 91 anchored as at 92 to one side of the room. One end of the cable is twined about the winding drum 72 while its opposite end is connected to a ring 93 from which extends a pair of cables 94 and 95, attached respectively to the eyelets 75' and 76', as shown in Fig. 14. With the parts thus arranged, winding movement of the drum will cause the machine to be bodily moved from the left towards the right, as viewed in said figure. Should it be desired to bodily move the machine in the opposite direction, the sheave 91 would be anchored at the opposite side of the room, and the cables 94 and 95 attached to the eyelets 75 and 76.

As previously pointed out, the construc-

130

tion of the cutting head is such as to form a very compact structure due to the close positioning of the cutting disks at the opposite sides of the plates 50, 50', and the method of associating the several parts forming the entire head. In fact, in actual practice, the cutting disks 53 and 53' are spaced less than an inch apart, forming a cutting head capable of producing comparatively narrow 10 kerfs.

It is also pointed out that the peculiar mounting of the cutting teeth upon the disks 53 and 53' not only provides a convenient method of removably securing the teeth in 15 operative position, but due to the symmetrical formation of the openings 58 and the base portions of the teeth, the teeth may be reversed so as to function for effective cutting action regardless of the direction of 20 rotation of the cutting disks with respect to the beam on which they are mounted.

The effective length of the beam 21 between the hub 32 and the sprocket gear 30 may be readily varied by means of rotating 25 the shaft 22 whereby to slide the rear portion 21" upon the terminal portion 21' of the forward section. The shaft 22 therefore serves as a means for varying the tautness of the chain 31.

30 The entire machine is constructed of such proportions that the same may be readily transported from place to place, and the distance between the cutting disks is such as to enable it to be effectively used under 35 crowded circumstances and for the purpose of securing the removal of very thin veins of coal or similar material which would be very difficult of access or uneconomical to mine with many of the mining machines now 40 in use.

While the preferred embodiment of the invention has been illustrated and described, it is apparent that many changes in details 45 of construction may be made without departing from the spirit of the invention, and is therefore not intended to limit the invention beyond the scope particularly defined by the appended claims.

I claim:

50 1. A mining machine comprising a frame, supporting means fixed to the opposite ends of the frame, a driving shaft rotatably mounted in said supporting means, a bodily movable beam slidably carried by said frame, cutters mounted at the free end of the beam, gearing interposed between said shaft and cutters for rotating the same, and means associated with said supporting means for manually applying power to the opposite 55 ends of said driving shaft.

2. A mining machine comprising a frame, a driving shaft rotatably mounted on the

frame, a bodily movable beam slidably carried by said frame, cutters mounted at the free end of the beam, a pinion journaled in the opposite end of the beam and splined to the driving shaft, a bearing pedestal carried by the beam, an auxiliary shaft journaled in the pedestal, a gear fixed to the upper end of the auxiliary shaft meshing with the said pinion, a sprocket gear fixed to the lower end of the auxiliary shaft, operative connections between the sprocket gear and cutters for rotating the same, and means for applying power to both ends of the driving shaft.

3. A mining machine comprising a frame, a driving shaft rotatably mounted on the frame, means for applying power to the driving shaft, a bodily movable beam slidably carried by the frame, cutters rotatably mounted on the free end of the beam, operative connections between the driving shaft and said cutters, a screw shaft anchored in the frame, said screw shaft engaging the beam whereby rotation of the screw shaft will reciprocate the beam within the frame, means for rotating the screw shaft, and means for selectively connecting the last-named means with the first said means for applying power to the driving shaft.

4. A mining machine comprising a frame, a driving shaft rotatably mounted on the frame, a bodily movable beam slidably carried by said frame, cutters mounted at the free end of the beam, a bearing pedestal fixed to the beam adjacent its opposite end, an auxiliary shaft journaled therein, gears fixed to the opposite ends of the auxiliary shaft, operative connections between the driving shaft and one of said gears, an operative connection between the remaining gear and the said cutters, a screw shaft rotatably anchored in the frame, a threaded boss on the pedestal cooperating with the screw shaft whereby rotation of the screw shaft will move the beam longitudinally of the frame, and means for selectively connecting and disconnecting the screw shaft with the driving shaft.

5. A cutting head for mining machines comprising a pair of rotatable discs, each of said discs being provided with a series of circumferentially spaced teeth, a portion of the teeth being of greater size than the remaining ones with those of smaller size interposed between those of larger size, the larger teeth projecting laterally away from the head, and those of smaller size for being directed laterally toward the space between two discs.

In testimony whereof, I sign my name.

HESS P. MORGAN.
